DISCHARGE CHUTE ASSEMBLY FOR MAGNETIC CLARIFIER

Alfred W. Gardes and Nicholas Dudchik, Lebanon, Ind., assignors to Houdaille-Hershey of Indiana, Inc., a corporation of Indiana

Application February 21, 1952, Serial No. 272,827

7 Claims. (Cl. 210—1.5)

This invention relates to improvements in a discharge chute assembly for a magnetic clarifier, and more particularly to a discharge chute assembly for use in connection with a clarifier having magnetized pickup means rotating in a bath of liquid to be cleansed of magnetic foreign particles, the invention being highly desirable for use in connection with a magnetic clarifier for coolant and cutting oils and the like, although the invention will have other uses and purposes as will be apparent to one skilled in the art.

In the past, some difficulty has been experienced in the removal of swarf, or the accumulation of gathered magnetic particles, from the rotary magnetized pickup means of magnetic clarifiers. This difficulty was frequently caused by the variances in consistency of different liquids being clarified. For example, where a discharge chute assembly effectively carries off accumulated swarf without the loss of more than a negligible quantity of the liquid for what may be termed a light oil, the same chute assembly would not be satisfactorily effective with a heavy oil, because an undue and undesirable amount of that oil would travel over the chute along with the swarf. It is extremely difficult to adequately reclaim liquid commingled with the swarf. Consequently, a magnetic clarifier would have to be constructed to operate upon liquid within a limited range, or else discharge assemblies would have to be changed when liquids of different consistencies were utilized.

With the foregoing in mind, it is an important object of the instant invention to provide a discharge chute assembly of simple construction which is readily adjustable to compensate for differences in consistencies of the liquids being cleansed.

Another object of the invention resides in the provision of a discharge chute assembly having portions thereof arranged at an angle to each other, and this angle of the chute assembly is readily and easily variable in keeping with the consistencies of the liquids undergoing clarification.

Still another object of the invention resides in the provision of a simple and very economical chute assembly for a magnetic clarifier, which may readily be adjusted to compensate for variances in consistency of the liquids being clarified without removal of the assembly from the clarifying apparatus.

Still a further feature of the invention resides in the provision of a discharge assembly for a magnetic clarifier, which assembly may readily be adjusted to compensate for variances in consistency of the liquids being clarified, and the adjustment may be effected while the clarifier is in operation and in an extremely short interval of time, whereby material saving results in that the labor is minimized and there is no need for shutting down the machine for frequent trials when a liquid of different consistency than that formerly undergoing treatment is to be cleaned.

While some of the more salient features, characteristics and advantages of the instant invention have been above pointed out, others will become apparent from the fol-

lowing disclosures, taken in conjunction with the accompanying drawing, in which—

Figure 1 is a pictorial view of a magnetic clarifier equipped with a discharge chute assembly embodying principles of the instant invention; and

Figure 2 is an enlarged fragmentary vertical sectional view through the structure of Fig. 1, illustrating the discharge chute assembly in side elevation.

As shown on the drawings:

10 At the outset, it may be best to mention that the magnetic clarifier with which the instant invention is associated, is more fully set forth, described, and claimed, in an Alfred W. Gardes copending application entitled Magnetic Clarifier and Method of Clarifying, filed February 8, 1951, Serial No. 210,060.

The magnetic clarifier with which the instant invention is shown in operative association comprises in general a base portion 1 which also functions as a reservoir for any overflow of liquid to be cleansed. Such overflow returns to the sump, tank, or other location of contaminated liquid through an outlet pipe 2. Near one end of the base is an upstanding frame portion 3 having a laterally extending wing 4 thereon. This frame portion together with an upstanding tank-like structure 5 at the other end of the base provides support for a removable tank 6 through which the contaminated liquid flows during the cleansing operation.

After being cleaned by magnetic means to be later described, the filtrate or cleansed liquid enters the structure 30 5 which forms a reservoir therefor, and exits therefrom through a pipe 7 to return to the cutting, grinding, or other type of machines with which the liquid functions as a coolant or cutting oil.

As seen in Fig. 2, the tank is baffled both longitudinally and transversely thereof as indicated at 8 to insure the liquid coming in contact with the magnetic pickup means. A flared inlet 9 divided to seat over the baffles as indicated by dotted lines in Fig. 2 supplies contaminated liquid in one end of the tank.

40 Journaled in opposite ends of the structure is a rotary shaft 10 which may be driven by way of a suitable electric motor 11 or other power device, through a gear reduction arrangement generally indicated at 12. Carried on this shaft within the tank 6 is a series of magnetic rings or disks 13, 14 and 15 in spaced relationship. These disks are separated by a ring magnet 16, preferably of a strong permanent variety, the ends of which contact the inside faces of confronting disks. The shaft 10, of course, is preferably of non-magnetic material, and around each ring magnet, but spaced therefrom, is a non-magnetic drum 17.

As liquid flows through the tank, magnetic foreign particles are removed from the liquid by the magnetic pickup disks 13, 14 and 15 rotating therein, and the swarf will accumulate on the exposed circumferential portions of these disks, and some will possibly be carried along on the adjacent surface of the nonmagnetic drum 17.

The instant invention centers itself with the removal of the accumulated swarf from the magnetic pickup means. For this purpose a discharge assembly has been provided, and this assembly is preferably mounted upon a stationary rod or shaft 18 secured at one end in the wing 4, and at the other end in a lug 19 projecting from the aforesaid reservoir 5. Substantially centrally disposed on the supporting rod 18 is a fixed flat faced lug 20 having an internal threaded bore to accommodate a holding screw. A discharge chute 21 having upstanding side flanges 22—22 is adjustably secured to the fixed lug 20 by means of a screw 23 extending through a cover plate 24 and engaged in the lug 20 through an elongated slot 25 in the chute 21. The cover 24, of course, prevents the discharged swarf from entering the slot 25.

3

Obviously, the chute may be adjusted upwardly or downwardly the extent of the slot 25.

At the upward and forward end of the chute 21 is an element 26 which for the purpose of convenience may be termed a scraper, this element having side flanges 27-27. The scraper 26 is hingedly connected to the chute 21 by means of a piano hinge indicated at 28 in Fig. 2. As seen in Fig. 1, the scraper 26 is notched in its forward end so as to extend over and between the pickup rings 13, 14 and 15. This element 26 need not actually provide scraping contact with the circumferential face and side margins of the pickup rings, or with the surface of the non-magnetic drum 17 therebetween, but only need approach these surfaces. A brush-like accumulation of swarf will be carried by the pickup rings, and this accumulation will assemble far in advance of the end of the scraper so that the pickup rings and drum therebetween are wiped clean by the brush accumulation, and this accumulation will travel over the surface of the scraper 26 until it reaches the inclined chute 21.

As seen clearly in Fig. 2 at 29, the side flanges 27 of the scraper extend slightly inside in overlapping relationship with the side flanges 22 of the chute.

The angle between the scraper and the chute may be selectively adjusted, and to this end, on each side of the assembly, a link 30 is pivoted as at 31 to the scraper flange 27, and the opposite end of this link is provided with an elongated slot 32 through which a bolt 33 mounted in the side flange 22 of the chute extends and may be locked in any suitable position of adjustment. It will be noted that in every instance, the screw heads of the respective bolts and pivots are located on the inside so as to interfere as little as possible with the movement of the swarf.

In operation, the instant invention is extremely simple and highly effective. Assuming that the liquid being clarified is what may be termed a relatively heavy oil, a relatively sharp angle between the scraper 26 and the chute 21 is desirable to prevent a quantity of this liquid traveling over with the swarf and down the chute. When this is the case, the discharge assembly may be adjusted to the full line position of Fig. 2, wherein it will be noted that the scraper terminates to the left of the vertical center line of the pickup means, these means rotating clockwise as seen in this figure. It will also be noted that the scraper is upwardly inclined, and this inclination will not affect the movement of the swarf, but will discourage the heavy oil from climbing to the entrance of the chute.

On the other hand, when a relatively light oil is being clarified, the discharge assembly may be adjusted to the dotted line position seen in Fig. 2, wherein the angle of elevation on the scraper is materially lessened, since the lighter oil will not have the tendency to follow the swarf that the heavier oil does. It will be apparent, therefore, that by manipulation of the bolt 33 on each side, and the screw 23, that substantially any desirable angle may be attained between the scraper 26 and the chute 21 in keeping with the consistency of the liquid being clarified. It will be especially noted that the structure is simple in its adjustment, and the adjustment may be made while the clarifying apparatus is operating. Obviously, the discharge assembly need not be removed from the machine, is economical, and highly durable. The discharge chute 21, of course, may lead to any suitable receptacle for the swarf.

It will be understood that modifications and variations may be effected without departing from the scope of the novel concepts of the present invention.

We claim as our invention:

1. A discharge assembly for a magnetic clarifier, including a downwardly inclined chute for the discharge of swarf, a scraper element pivoted to the upper end of the chute and having a free edge portion for disposition in

proximity to the pickup drum of a clarifier, each of said chute and scraper element having upstanding side flanges, a link pivoted to a side flange of the scraper element, said link having an elongated slot therein at the other end, and means on the side flange of the chute extending through said slot to anchor the link in a position of adjustment.

2. A discharge assembly for a magnetic clarifier, including a downwardly inclined chute for the discharge of swarf, a scraper element hingedly connected to said chute at the upper end thereof, adjustable means to hold the angle between the scraper and chute at a desired degree with an edge of the scraper in proximity to the pickup drum of a clarifier, said chute having an elongated slot in an intermediate location thereof, and means extending through said slot to anchor the chute to a supporting member in a desired position of adjustment.

3. A discharge assembly for a magnetic clarifier, including a downwardly inclined chute for the discharge of swarf, a scraper element hingedly connected to said chute at the upper end thereof, adjustable means to hold the angle between the scraper and chute at a desired degree with an edge of the scraper in proximity to the pickup drum of a clarifier, said chute having an elongated slot in an intermediate location thereof, a cover over said slot, and securing means extending through said cover and slot for engagement with a supporting member.

4. In combination with a magnetic clarifier having rotary magnetic pickup means and a fixed discharge assembly support, a downwardly inclined chute connected to said support, a scraper element pivoted to the upper end of said chute with an edge in proximity to said pickup means, and adjustable means associated with said chute and scraper element to selectively determine the angle therebetween and selectively vary the angle between the scraper and pickup means.

5. In combination with a magnetic clarifier having rotary magnetic pickup means and a fixed discharge assembly support, a chute connected to said support, said chute being outwardly and downwardly inclined relatively to the pickup means, a scraper element pivotally connected to the upper end of said chute and outwardly and upwardly inclined relatively to the pickup means with an edge thereadjacent, and adjustable means to selectively vary the angle of inclination of said scraper element and selectively vary the angle between the scraper and pickup means.

6. In combination with a magnetic clarifier having rotary magnetic pickup means and a fixed support spaced therefrom, a discharge assembly including a downwardly inclined chute and a scraper element pivoted to the upper end of the chute and disposed at an angle thereto with an edge in proximity to said pickup means, adjustable means interconnecting the chute and scraper element to selectively vary the angle therebetween, said chute having an elongated slot adjacent the fixed support, and means extending through said slot to anchor the chute to the fixed support.

7. In combination with a magnetic clarifier having rotary magnetic pickup means and a fixed support spaced therefrom, a discharge assembly including a chute and a scraper end portion thereon and disposed at an inclination to the rotary pickup means, an edge of said end portion being in proximity to said pickup means, means to connect the assembly to the fixed support, and adjustable means to vary the inclination of said scraper end portion relatively to the pickup means.
